UNITED STATES PATENT OFFICE

2,127,052

AIR-COOLED SAFETY TIRE

Earl Von Bon Horst, San Clemente, Calif.

Application February 16, 1938, Serial No. 190,837

5 Claims. (Cl. 152—153)

This invention relates to an air-cooled safety tire.

An object of the invention is the construction, preferably from a single blank, of a novel rim-structure including a central rim unit and outer rim units, held in their folded or final position by an efficient spoke arrangement.

Another object of the invention is the construction of a rim-structure which includes an air-cooled unit, and which rim-structure is of considerable strength, while at the same time being comparatively simple and inexpensive to construct.

A still further object of the invention is to improve the construction of an air-cooled safety tire, as shown and specifically described in my prior United States Patent No. 2,097,748, issued November 2, 1937.

With the foregoing and other objects in view, my invention comprises certain novel constructions, combinations and arrangements of parts as will be hereinafter fully described, illustrated in the accompanying drawing, and more particularly pointed out in the appended claims.

25 In the drawing:

Figure 1 is a transverse, vertical, sectional view of a tire constructed in accordance with the present invention.

Figure 2 is a longitudinal, sectional view taken 30 on line 2—2, Fig. 1.

Figure 3 is a fragmentary, perspective view of a device constructed in accordance with the present invention.

Figure 4 is a fragmentary, plan view of a blank 35 prior to bending or folding into the final shape of the device, as seen in Figure 3.

Figure 5 is an enlarged fragmentary, vertical, sectional view of the device, showing particularly the spoke attaching feature, while

40 Figure 6 is a similar view of another embodiment.

Referring to the drawing by numerals, 1 designates preferably a hollow spoke of an ordinary wheel (not shown) to which is secured in the 45 manner hereinafter described, the rim-structure which is preferably formed from a single blank, as illustrated in Figure 4. This rim structure comprises a central rim unit 2 and integral outer rim units 3. The central rim unit 2 comprises a hollow body portion 4 terminating in inwardly-extending parallel legs 5. These legs 5 are provided with pairs of registering spacing lugs 6 that are normally in engagement at their inner ends, when the blank has been folded, as shown 50 in Figure 3. These lugs 6 may be of the form

shown, or may be of the form shown in Figures 6 to 8 of the drawing in my prior U. S. Patent No. 2,097,748, as the constructor desires.

The legs 5 terminate at their inner ends in outwardly-extending flat portions 7, which flat 5 portions 7 terminate at their outer edges in upwardly-extending angular flanges 8.

The novel spoke construction comprises placing the inner end of the spoke, or spokes 1, so as to bridge across the outer ends of legs 6, with 10 each spoke secured, as by welding 9 (Fig. 5) to the flat portions 7 of the outer rim units (Figs. 3 and 5). By this arrangement the rim structure cannot spread apart, even though undue pressure is placed thereon, besides the parallel legs 15 are held in a substantial and true position for keeping a sufficient clearance to allow free air circulation into the air-cooling chamber 10, for best results. The spacing lugs 6 will prevent 20 closing of the passage between the parallel legs, even though some undue pressure, as accidental bending, is placed upon the rim-structure.

In Figure 6 there is shown a modification of the rim-structure, in which sockets 11 are formed; these sockets being screw threaded on their outer 25 wall to receive the screw threads 12 of spokes 1a. In this manner a very efficient attaching means is provided, insuring too of the uniform spacing of the legs of the central rim unit, holding the folded blank in an efficient position, once 30 it has been assembled or formed into shape, as seen in Figures 1 and 3.

In Figure 4, the valve aperture 13 is formed for receiving the valve unit 14. The lugs 6 are pressed in the blank, and the dotted lines 15 represent the position of the spokes 1 and 1a in the assembly. The spokes are placed on what might be called the lines of fold 16, Fig. 4, and when so placed they act to lock or bind the blank in its folded position. Therefore, it will be understood that the spokes support the rim-structure; they also perform the additional function of holding the legs 5 in their normal parallel position, while at the same time they do not interfere with the free circulation of cooling air into the interior of the tire. 40

A standard shoe 17 is placed upon the rim-structure in any suitable manner. This shoe 17 has an outer hard rubber thread 18 with an inner fabric unit 19. An inner tube 20 is placed 50 in the shoe 19 and this tube 20 conforms to the shape of the shoe and the central rim unit 2. The central rim unit 2 is faced or covered on its outside with a light weight canvas 21. The valve unit 14 extends at its inner end into the 55

compartment or chamber formed by tube 20, in the same manner described and shown in my prior Patent No. 2,097,748.

This improved tire does not in any way affect the true running qualities of the wheels on which it is mounted, and adds very little weight over an ordinary tire, while the tire of this invention is cooled by drawing off the traction heat. This invention also practically eliminates any dangers attended on a blow-out, because if a blow-out occurred the wheel would only drop about two to two and one-half inches or no more than if the tire was under-inflated, as indicated clearly by dotted lines "A", Fig. 1. This position shown by dotted lines "A" would prevent the squeezing of the shoe out from under the edges of the primary rim, and thereby eliminate the sharp swerving of the car, whereby accidents occasioned by blow-outs are prevented, inasmuch as the car is allowed to travel in a straight line to a normal stop. Of course, if necessary, the car could be driven on the deflated position, as indicated by dotted lines "A".

It is to be understood that I may use solid spokes in this invention (not shown) if I desire, for by reason of forming my rim-structure in one piece or out of a blank, an open-ended slit, so to speak, is formed between the parallel legs, permitting free entrance of air into the cooling chamber 10, without impairing the efficiency of the spokes, in so far as they are excellent supporting means for the rim-structure as well as the binding or locking means for holding the rim-structure from spreading, including the retaining of the parallel legs 5 in their true assembled position.

While I have described the preferred embodiments of my invention and illustrated the same in the accompanying drawing, certain minor changes or alterations may appear to one skilled in the art to which this invention relates during the extensive manufacture of the same and I,

therefore, reserve the right to make such alterations and changes as shall fairly fall within the scope of the appended claims.

What I claim is:

1. In an air-cooled tire, the combination of a rim-structure including a central rim unit provided with parallel legs having radially inner ends, and spokes having their radially outer ends directly attached to the radially inner ends of said parallel legs. 5

2. In an air-cooled tire, the combination of a rim-structure including parallel legs terminating at their radially inner ends in flat portions, spokes secured at their radially outer ends directly to said flat portions and spanning the distance between the radially inner ends of said legs, and each spoke serving as a fastening means for securing said legs in their assembled position. 10

3. In an air-cooled tire, the combination of a rim-structure including spaced legs having radially inner ends integral with horizontal flat portions, said flat portions and the radially inner ends of said legs provided with screw-threaded sockets, and spokes having their radially outer ends screwed into said screw-threaded sockets 20 and spanning across the space between said legs. 25

4. In an air-cooled tire, the combination of a rim-structure provided with spaced legs having radially inner ends and spaced outer rim portions, and spokes having their radially outer ends 30 directly engaging and supporting said outer rim portions and fixedly securing said spaced legs in spaced position.

5. In an air-cooled tire, the combination of an inner sheet-metal rim unit comprising parallel legs provided at their radially inner ends with integral outstanding flat portions, a spoke having its radially outer end secured to the radially inner ends of said parallel legs and the flat portions, and the radially outer end of said spoke also 40 bridging the space between said parallel legs. 35

EARL VON BON HORST.
